UNITED STATES PATENT OFFICE.

HARVEY E. EDGINGTON, OF KANKAKEE, ILLINOIS, ASSIGNOR OF ONE-HALF TO
ALBERT C. TANNER, OF KANKAKEE, ILLINOIS.

STONE-SURFACING APPARATUS.

Application filed March 7, 1921. Serial No. 450,243.

To all whom it may concern:

Be it known that I, HARVEY E. EDGINGTON, a citizen of the United States, and a resident of Kankakee, in the county of Kankakee and State of Illinois, have invented certain new and useful Improvements in Stone-Surfacing Apparatus, of which the following is a full, clear, and exact specification.

10 My invention is concerned with stone surfacing tools, and similar devices, where a pneumatic hammer is employed and in its operation produces dust and clippings of any character that can be moved pneumatically, and it consists mainly in a novel combination of elements wherein a funnel or nozzle is placed adjacent where the tool is working and is connected by a pipe with an exhaust pipe from the hammer so that the 15 exhaust from the cylinder will create a suction in the tube leading from the nozzle to draw the dust into the nozzle, through its pipe and into a discharge pipe through which the exhaust escapes carrying the dust 20 with it to a point where it cannot harm the workman.

To illustrate my invention, I annex hereto a sheet of drawings in which the same reference characters are used to designate 25 identical parts in all the figures, of which—

Fig. 1 is a side elevation of an apparatus embodying my invention;

Fig. 2 is an enlarged perspective view of 30 a nozzle which I employ in connection with the apparatus; and

Fig. 3 is a detail in section on line 3—3 of Fig. 1.

In carrying out my invention, I have shown it as applied to a pneumatic surfacing tool *a* having the customary supporting rollers *b* and guide rollers *c* co-operating with the track rail *d* adjustably secured on the vertical standard *e* by any desired means. The cylinder of the pneumatic hammer is provided with the customary air supply pipe *f* and with an exhaust pipe *g* extending from the exhaust port of the hammer, as seen, and terminating in the dust discharging pipe *h*, which preferably extends out through a window and is guided by the roller *i* mounted on the frame of the rail *d*, as seen in Fig. 3. The end of the pipe *h* is provided with a T *j*, the horizontal ends of which are connected to the pipes *h* and *g* and the lower end of which is connected to

the flexible tube *k*, which has its lower end connected to the nozzle *l*, which, as seen, has the flaring end with the opening widened at the center as seen in Fig. 2. To support this nozzle at the proper elevation relative to the end of the reciprocating tool *m*, I preferably form a boss *n* on the upper surface thereof in which boss is secured the rod *o* which extends up through an aperture in the flange *p* secured on the head of the cylinder of the hammer, where it is held in place by the thumb nut *q*, as shown. The tool *m* is provided with a suitable washer *r* which prevents the dust being blown away from the nozzle *l* by any downward leakage of the compressed air from the cylinder.

The operation of the device will be readily apparent:

As the tool *m* reciprocates under the strokes of the piston *s* in the cylinder, the exhaust from the cylinder is shot out through the pipe *q* into the pipe *h*, creating a suction therethrough which draws the air with the dust from the tool into the nozzle *l*, up through the pipe *k* and out through the pipe *h* in a manner which will be readily understood. I have found that with my apparatus, substantially all of the dust from the tool can be removed, thus making it very desirable in the protection afforded to the operator.

While I have shown and described my invention in the form which I at present consider best adapted to carry out its purposes, it will be understood that it is capable of modifications and that I do not desire to be limited in the interpretation of the following claims except as may be necessitated by the state of the prior art.

What I claim as new and desire to secure by Letters Patent of the United States is:

1. In an apparatus operated by compressed gas, the combination with an engine cylinder having an exhaust pipe leading therefrom, of a piston in the cylinder, a tool operated by the piston, a suction nozzle adjacent the working end of the tool and in use freely open to the air, a flexible pipe leading from the nozzle into which the exhaust pipe opens to create a draft therethrough, sucking air into the nozzle and adjustable means for supporting the nozzle.

2. In an apparatus operated by compressed gas, the combination with a sup-

porting frame having a horizontal track bar, of an engine cylinder having an exhaust pipe leading therefrom and mounted to travel on the track bar, a roller on the frame, a pipe parallel to the track and resting on the roller and having the exhaust pipe opening through one end thereof to create a draft therethrough, a piston in the cylinder, a tool operated by the piston, a suction nozzle adjacent the working end of the tool, and a branch pipe leading from the nozzle into the parallel pipe and secured to the same, and means for supporting the branch pipe from the engine cylinder.

3. In an apparatus operated by compressed gas, the combination with a supporting frame having a horizontal track bar, of an engine cylinder having an exhaust pipe leading therefrom and mounted to travel on the track bar, a roller on the frame, a pipe parallel to the track and resting on the roller and having the exhaust pipe opening through one end thereof to create a draft therethrough, a piston in the cylinder, a tool operated by the piston, a

suction nozzle adjacent the working end of the tool, a branch pipe leading from the nozzle into the parallel pipe and secured to the same, a rod secured at its lower end to the nozzle and having its threaded upper end extended through an apertured lug on the engine, and a nut on the rod for the purpose described.

4. In an apparatus operated by compressed gas, the combination with an engine cylinder, of a reciprocating tool extending therefrom, means at the working end of the tool to collect and carry away the dust formed thereby, and a shield carried by the tool and serving to deflect any air leaking from the cylinder toward the working end of the tool from reaching said working end and scattering the dust.

In witness whereof, I have hereunto set my hand and affixed my seal, this first day of March A. D. 1921.

HARVEY E. EDGINGTON. [L.S.]

Witnesses:

V. S. ELLIS,
BERNEICE L. KLOUTCHER.
